UNITED STATES PATENT OFFICE

WEBSTER I. SALLEE, OF ROCKY RIVER, OHIO

DRYING APPARATUS AND PROCESS

Application filed December 3, 1929. Serial No. 411,279.

This invention relates to a process and apparatus for drying loose materials such as may be handled by belt conveyors, tumbling and rotating drums and the like and 5 is particularly concerned with the drying of sand or comparable materials.

The efficient and economical drying of sand and like materials requires economical utilization of heat to free the moisture from the 10 sand, a conveying media to carry away the moisture quickly when separated from the sand, accurate regulation of the heating and conveying media throughout a wide range, to eliminate the danger of overheating the 15 materials and apparatus, efficient handling of the material while being dried.

An object of my invention is to accomplish this purpose by applying to a continuously progressing and tumbling stream of 20 sand accurately regulated heat evenly distributed along the path of the moving sand stream, and by passing the hot, dry heating and conveying media through the tumbling sand in intimate contact with the individual 25 particles to absorb and carry away the freed moisture and to free and remove any remaining moisture.

Another object of my invention is to obtain an accurate wide range of regulation of the 30 heating and conveying media by means of independent controls for the fuel, various air supplies, and direction and shape of the heating flame.

Another object is to obtain combustion of 35 the heating media throughout a large portion of its path so that heat is evenly distributed thus eliminating concentrated heats at any point with consequent damage to the material or apparatus, and excessive heat loss by 40 radiation.

Another object of my invention is the utilization of a cheap fuel and inexpensive durable apparatus for obtaining these results.

More specific objects include providing 45 means for governing the temperature of fuel passing to the burner and for adjusting the shape and velocity of the forcible air stream surrounding the burner and flame.

Another specific object is controlling the 50 amount of fuel fed to the burner automati-

cally, depending upon the heat of the material discharged from the drier.

Other objects and advantages are set forth in my copending application Ser. No. 429,- 519, filed Feb. 19, 1930, which describes the 55 method of burning fuels which may be accomplished with the burning apparatus herein described; and in my copending application Ser. No. 512,766, filed Feb. 2, 1931, which describes in detail the fuel burning apparatus 60 herein briefly set forth in connection with the drier.

In carrying out my invention I use an inner drum or flue mounted within an outer drum and separated therefrom, forming a 65 passage for the loose materials to be dried. It has been found that if heat is merely directed through this inner flue, more or less satisfactory drying may be accomplished. However, to greatly increase the efficiency of 70 such drying, using much greater heats, I cause a return of the hot gases or products of combustion, after passing through the inner drum, along the passage between the drums and through the material. 75

For economy in fuel consumption, as I stated, I use a low grade fuel and I find that the inner flue, if sufficiently refractory to withstand a direct action of combustion or attack of the flames, correspondingly effects 80 an insulation, and difficulty is encountered in accomplishing even distribution of the heat through the inner drum or flue.

I therefore combine with this inner drum or flue a burner arrangement including a refractory combustion chamber, in which combustion may be largely or substantially completed, and without waste of fuel, and by forcible air streams, I may govern the combustion for wide variations while directing 85 the products of combustion in the flue.

An auxiliary air stream may be drawn into the flue for further heat distribution and completion of combustion. Still an additional air stream may be united with the returning 90 products of combustion as will be hereinafter described.

The particular construction and arrangement of the burner and the combustion chamber which I found successful, forms the sub-

ject matter of an application about to be filed by me.

In the drawings—

Fig. 1 is a side elevation of my drying apparatus.

Fig. 2 is an enlarged side elevation of the heating unit for the apparatus shown in Fig. 1.

Fig. 3 is an enlarged longitudinal section 10 through the fuel gun and register of the heating unit shown in Fig. 2.

Fig. 4 is an enlarged transverse view of the heating unit and air supplying means, taken on line 4—4 of Fig. 3.

Fig. 5 is an end elevation of the heating unit.

Fig. 6 is a transverse sectional view of the drier taken on line 6—6 of Fig. 1.

Fig. 7 is an end elevation of the discharge end of the drier, a portion being removed for clearness of illustration.

An apparatus found very satisfactory for carrying out the above named object, as well as other objects which will become apparent, is fully described in the following specification, wherein reference is made to the drawings by reference numerals, the same numerals designating the same parts in the various views.

30 As illustrated, a preferred form of apparatus for this process includes a drier proper consisting of a long substantially and horizontal cylinder or drum sloped slightly from intake end at the right, to the discharge end 25 at the left of figure. This cylinder 1 is the outer cylinder of the drier and is suitably mounted to revolve upon rollers shown as bearing against supporting rings 5 encircling the drum, the rotation being effected by a gear 40 ring 7 surrounding the drum and meshing with a pinion 8, on the shaft of a suitable motor 10. Within the cylinder 1 is an inner drum or flue 12 spaced from the outer cylinder and preferably carried by suitable supporting bolts 14 secured thereto and slidably extending through the cylinder 1, to allow 45 for relative changes due to expansion. Springs, such as 15, surrounding the supporting bolts may be interposed between the cylinder 1 and bolt heads or nuts 16.

50 At the entrance end of the cylinder 1, is shown a cone-like enlargement or bell 13 spaced from and shaped substantially complementary to the discharge end of heater 20 55 to be presently described.

The cylinder 12 at the discharge end stops short of the end of the cylinder 1. Mounted on spaced apart supports 17 in the cylinder 1, is a somewhat saucer-shaped baffle or deflecting plate 18, shown as having an inturned 60 perimeter acting to deflect the gas stream from the cylinder 12 outwardly and back between it and the cylinder 1 to a suitable exhaust stack 22. As the cylinder 1 is revolved, its position on the rollers 3, may be

maintained by flanges or a roller as shown at 4.

The sand or other materials may be fed to cylinder 1, by any suitable means. I prefer to bring it from a storage bin or any other source to a hopper 30 from which it is discharged onto a belt conveyor indicated at 32 which delivers it onto a deflector or chute 35, extending into the end of the cylinder 1. The material is caused to pass through the cylinder 1 as it rotates by reason of fins or inwardly projecting plates 36 within the cylinder. As shown these are arranged to carry the sand up as the cylinder revolves and cause it to spread and fall over cylinder 12. By reason of the slope of cylinder 1, sand is advanced slowly by this action to the exit end where it discharges onto a suitable chute such as indicated at 40 which may deliver it to any conveyor, vehicle or receptacle as desired.

85 My heating unit 20 consists of a primary combustion chamber 21, shown as a metal cylinder lined with a suitable refractory material such as fire brick 50 and contracted at the discharge end to form a cone-like portion 51 and a nozzle-like portion 52. The other end of this combustion chamber is sealed by a suitable plate 54 provided with a peep hole 56, having a central opening adapted to receive the air register 60, in which is mounted a fuel gun 58.

For this purpose, I may use and have shown an oil gun and register of Letters Patent of the United States No. 1,680,455, making certain modifications therein to meet my requirements.

100 As shown, the oil gun 58 comprises a cylindrical casing 62, in which a spinner 64 is rotatably mounted in suitable bearings 66. The spinner is provided with an air turbine 68 within the casing. Air under pressure, controlled by a suitable valve 70, is supplied to the gun casing 62 from a fan 72 through a conduit 74. This air passes through the turbine 68 and causes it to rotate 110 110 and the spinner at a very high speed.

Oil is fed to the gun 58 under a very low pressure from a reservoir through a conduit 75, the amount being controlled by a valve 76. The conduit 75 extends into the gun casing and joins the hollow shaft of the spinner 64, through which the oil is directed into the inside of the spinner, which gives a high rotary speed to the fuel and throws it out as a cone-like sheet at the end.

120 Teeth or projections, not shown, on the exit end of the spinner strike the oil as it leaves the cup and impart additional rotary motion thereto, which helps to break the oil into a mist of fine globules.

125 The air supplied, after passing through the turbine, passes out of the end of the gun, casing around the spinner, and, by means of fins about the inner surface of the casing, is given a rotary motion in a direction oppo-

site to that of the sheet of oil. Since the oil sheet and air current are revolving in opposite directions, the oil strikes the air at a more abrupt angle, causing a very high degree of atomization.

The oil gun is mounted in a register 60 by means of a spider 80. The register in turn is mounted in a plate 54 of combustion chamber 21 and opens into the combustion chamber. Within the register 60 are a plurality of radial vanes 82 mounted on rock shafts 83. The inner ends of the shafts are pivoted in a collar about the gun casing, and the outer ends extend outside of the register.

These outwardly extending ends are bent over to engage notches in a flange of a ring 84 loosely mounted on the register, so that, when the ring 84 is rotated slightly about the register, the shafts are concurrently rotated about their axes, thus changing the angle of the vanes from approximately a common plane to inward open position.

An end plate 86, slidable axially of the register 60 on rods 88, provides a means for regulating the amount of air that can be drawn into the register by the action of the oil gun 68. The air entering the register is given a spiral motion, as it passes through the vanes 82, to control the shape of the flame.

For my purpose, I move the end plate 86 to its withdrawn position and between it and the register install a large sealed even pressure chamber 90 opening into the register 60. Air under pressure is supplied to this even pressure chamber from a power operated fan 92.

A series of shutters 94 operable by a suitable lever 96 are provided near the entrance 40 of the even pressure chamber to control the volume and pressure of air flowing into it. As shown, it is desirable to make this chamber much larger than the register opening in order that eddy currents will be broken up and more even pressure created, and consequently, a direct and even flow of air into the register may be obtained. The air thus supplied is given a spiral motion by the radial vanes 82, above described.

A large amount of air is supplied in proportion to the size of the combustion chamber, and consequently, a pressure is built up within the combustion chamber. As a result of this pressure and the spiral motion of the air thus supplied, a rotating column of burning oil and air is formed in the combustion chamber and retains a position in the combustion chamber fairly centrally thereof. This raises the temperature therein to a very high heat, and prevents oil striking the refractory walls of the combustion chamber.

The burning and heated air and oil are driven by this pressure and their initial velocity out of the combustion chamber 21 and into the cylinder or drum 12 of the dryer, into

which the nozzle-like portion 52 of the chamber 21 extends.

Combustion of this intermixture of heated and burning oil is completed within the cylinder 12 and may continue throughout a large part of the length of the inner cylinder 12, thus furnishing a large amount of heat very evenly distributed therethrough. This eliminates the necessity for using a high degree of heat in the combustion chamber, with a consequent extremely high temperature at the entrance end of the inner cylinder 12, which might overheat the materials fed onto the inner cylinder 12.

To obtain better control over the distribution of heat and combustion of the mixture, I provide a tertiary air system. On the entrance end of the cylinder 12 is mounted a bell 13, having an inner surface contour, substantially complementary to the cone-like portion 51 and the nozzle-like portion 52 of the combustion chamber 21.

The combustion chamber is mounted so that it can be moved towards and away from the drum 12, thus increasing or decreasing the size of the opening 102 between the bell and the end of the combustion chamber 21.

Due to the rotary velocity of the burning mixture and the axial velocity at which it enters the cylinder 12, a large quantity of air is drawn into cylinder 12 through the opening 102, the amount being regulated by changing the size of the opening, as described. This tends somewhat to insulate the cylinder 12 for a portion adjacent to the heating chamber and absorbs some of the heat issuing therefrom, thus preventing a temperature high enough to damage the drum 12 or the materials. Furthermore, this additional quantity of air permits complete combustion of the large proportion of volatilized oil remaining in the burning stream, thus giving off heat from combustion through a great length of the drum 12.

The primary, secondary and tertiary air can be regulated independently so that the tertiary air absorbs only enough heat at the entrance of the drum 12 to obtain the desired lower temperature for the protection of the cylinder and materials. This heat is not lost but is utilized in raising the temperature of this volume of air so that union and combustion with the unburnt oil and gases are more rapid and obtained while this column of gases are passing through the drum 12.

Cylinder 12 is somewhat shorter than the outer cylinder 1, so that its discharge end is a short distance within the open end of the cylinder 1. Secured to the cylinder 1 by space-apart supports 17 and axially aligned with and placed a short distance beyond the discharge end of the cylinder 12 is a deflecting plate 18 above mentioned. This plate is formed to present an inturned center and

perimeter, so that the heated or burning gases impinging thereon, as they leave the inner drum at a high velocity, are turned back and passed rapidly between the drum 12 and the cylinder 1 in direct contact with the tumbling materials therein. This deflecting plate is somewhat smaller than the outer cylinder 1, leaving the space 103 between its periphery and the walls of the outer cylinder 1.

10 Due to the velocity at which these gases are deflected, a suction is created which draws air through the space between the outer cylinder and the deflecting plate. This additional air and the large volume of heated air 15 and gases already furnished, quickly absorb the moisture which has been driven out of the sand, due to its heating by contact with the heated drum 12. Since the sand is continuously tumbling, the surface of each particle is exposed to this draft of heated air, causing additional drying, and conveying away the moisture. Though combustion is usually complete when the heating media have reached the end of the drum 12, if any 20 portion happens to be unburned, this additional air insures complete combustion.

A suitable flue 22 is provided at the end of the outer cylinder 1 adjacent to the heating unit 20, to carry away moisture-laden gases 30 and air and discharge them into the open atmosphere.

It should be noted that the need of a large stack to create a draft is eliminated and that it is not necessary to have a stack sealed about 35 the end of the outer cylinder. As shown, a light metal stack may be provided with a loose-fitting hood extending slightly below the axes of the cylinders and open at the base.

40 In some cases, it is desirable to direct the flame at an angle to the axis of the drum 12, or parallel to, but offset from such axis. The desired angle or location may be obtained by raising or lowering one or both ends of the 45 combustion chamber 21.

Since this combustion chamber is supported on suitable legs, it may be lifted or lowered or moved axially or transversely of the cylinders 1 and 12, as desired, by blocking or in any 50 convenient manner. Suitable flexible couplings for the air and oil conduits are provided for this purpose as shown. Raising or lowering of the ends of the combustion chamber 21 may also be accomplished by screws 55 such as designated 110.

It is desirable to control the heat of the material fairly accurately. However, since at different times different amounts of moisture are in the air and in the material, and 60 the temperature of the air and materials may vary greatly, I make my control of heat dependent upon the temperature of the material as it is discharged from the drier. I may do this by means of a thermostatic switch 111 located at the discharge end of

the cylinder and which may be provided with a thin metal plate upon which the material falls as it is discharged from the drier. This thermostatic switch operates a mercuroid valve which controls the amount of fuel supplied.

I find it economical and desirable to heat the fuel oil, when starting operation with the burner, to insure atomization of the oil. I accomplish this by means of a heating coil 114. 75 Since it is desirable to use heated oil at all times during burning, I provide several turns of the oil feed conduit about the combustion chamber 21, enclosing the coil thus formed in a suitable housing 112.

As soon as the temperature of the combustion chamber 21 has been raised sufficiently, the heat therefrom preheats the oil as it passes through this coil, and the electric heating coil can be shut off.

It is apparent from the foregoing description that I have provided a sand drier which quickly and efficiently dries a large volume of sand under all conditions, and in which the range of use and accuracy of control is of a 90 very high degree.

Experience has demonstrated that I may effectively dry a very much larger tonnage of sand for a given fuel cost than by other devices and systems now in use. The operation of the device is simple, effective and comparatively inexpensive to install and requires but one attendant.

I claim:

1. A drier comprising an elongated drum, 100 a flue within and spaced from the walls of said drum, means to tumble materials to be dried progressively through said drum and onto said flue, a combustion chamber arranged to discharge into said flue at one end thereof, 105 said chamber being coaxial with said flue, a nozzle at the discharge end of said chamber for directing products of combustion from said chamber into said flue, said nozzle projecting into said flue, the end of said flue being flared around said nozzle and forming an annular passage between said nozzle and said flue, and said combustion chamber being movable toward and away from said flue whereby the size of said annular passage and the amount of air introduced therethrough is controlled, baffle means at the discharge end of the flue to return the products of combustion back between the flue and drum, and means to conduct material to be dried against the flue within said drum at the end adjacent to said combustion chamber.

2. A drier comprising an elongated drum, a flue within and spaced from the walls of said drum, means to continuously tumble loose materials through said drum and over said flue, said drum being open at the discharge end to permit free access of air, a combustion chamber arranged to discharge into said flue, 125 a fuel gun including means to discharge fuel 130

- and air into said chamber, a blower adapted to force air at a pressure above atmosphere into said combustion chamber, and means to regulate the amount of air from said blower, 5 an adjustable air inlet passage between the flue and combustion chamber through which a regulated volume of air may be drawn, baffle means to return said products of combustion back between the flue and drum, and 10 means to conduct the material to be dried against the flue within the drum at the end adjacent to the combustion chamber. 15
3. A drying apparatus comprising an elongated drum, a flue within and spaced from the walls of said drum, and means for progressively tumbling loose materials to be dried over said flue and through said drum, a combustion chamber at one end of the drum arranged to discharge into said flue, a fuel 20 gun in said chamber coaxial with said flue and spaced from the discharge end of said chamber, and means to force air and fuel into and through said gun, and means to blow air about said gun and into said chamber, said 25 drum being open at the discharge end, and a baffle arranged at the end of said flue and in the discharge end of said drum for returning the products of combustion from said flue back between the flue and drum. 30
4. A drying apparatus comprising an elongated drum, a flue within and spaced from the walls of said drum, and means for progressively tumbling loose materials to be dried over said flue and through said drum, a 35 combustion chamber at one end of the drum arranged to discharge into said flue, a fuel gun in said chamber coaxial with said flue and spaced from the discharge end of said chamber, and means for forcing air and small 40 particles of fuel into and through said gun, and means to blow air about said gun and into said chamber, said drum being open at the discharge end, and a baffle arranged at the discharge end of said flue and in said drum 45 for returning the products of combustion from said flue back between the flue and drum, and said last named means including a fan and an even pressure chamber communicating with said fan and said combustion chamber. 50
5. A drying apparatus comprising an elongated drum and a flue within and spaced from the walls of said drum, and means for progressively tumbling the materials to be dried over said flue and through said drum, a combustion chamber at one end of said drum, said 55 combustion chamber being contracted at one end to form a nozzle coaxial with said combustion chamber and flue and arranged to discharge into said flue through said nozzle, a fuel gun in said chamber at the end opposite the nozzle arranged to discharge a mixture of small particles of fuel and air into said combustion chamber whereby the mixture is ignited and partially burned, and means to blow 60 a forcible stream of air about said gun and into said chamber towards said nozzle for forcing an elongated burning column of flame into said flue and for supplying conveying media for the freed moisture, said flue being open at the discharge end, a baffle at the discharge end of said flue and within said drum arranged to return the products of combustion from said flue back between said flue and drum. 65
- In testimony whereof, I hereunto affix my 75 signature.
